UNITED STATES PATENT OFFICE.

WARREN LEMON, OF ST. LOUIS, MISSOURI.

DIRIGIBLE AIRSHIP.

Application filed October 6, 1925. Serial No. 60,749.

This invention relates to a novel form of dirigible airship, and the principal objects of the invention are to provide an airship having a plurality of gas bags disposed in a superimposed relation with each other, thereby arranging the longest axis of the airship in a vertical plane and enabling said airship to occupy minimum ground space in order to facilitate the descending and ascending thereof without sacrificing the lifting or carrying capacity of same.

Further objects of the invention are to arrange said gas bags or members independently of each other whereby the injury or incapacity of one or more of said members will not disable said airship but will permit it to land safely.

Still further objects of the invention are to provide an airship with a plurality of horizontally disposed propellers for driving the airship, and to provide a vertically disposed propeller for facilitating the ascending of the airship and enabling it to rise in a vertical plane when leaving the landing.

With these and other objects in view, my invention consists in certain novel features of construction and arrangement of parts, hereinafter more fully described and claimed, and illustrated in the accompanying drawings, in which—

Figure 1 is an enlarged side elevational view, partly broken away, of the airship.

Figure 2 is a top plan view of same.

Figure 3 is a side elevational view of the airship, showing in dotted lines the rudder folded against the airship.

Figure 4 is a horizontal cross section taken on line 4—4 of Figure 1.

Figure 5 is a horizontal cross section taken on line 5—5 of Figure 1.

Figure 6 is a horizontal cross section taken on line 6—6 of Figure 1.

Figure 7 is a detail view of a pulley over which operates the cable used for displacing the rudder.

Figure 8 is a detail view showing the flexible connection between one end of its gas member and the frame.

Briefly stated, the airship consists of a series of gas bags arranged in a vertical row and secured to a suitable framework, the lower end of which carries a car in which is mounted the engine utilized for driving the propellers of the airship. I do not wish to confine myself to any specific form of framework or specific construction of the gas

bags as any suitable form or construction may be used. The gas may be admitted to the bags in any conventional method and for this reason no valves or means for control-

5 60 ling the same are shown or described. Referring by numerals to the accompanying drawings, 10 indicates a series of gas bags arranged in superimposed relation and spaced apart a suitable distance. Each of these members which are of ovoidal shape are attached at their ends by suitable connections 11 and 12 to a framework 14 which extends upwardly and carries at its lower end a car 15 containing an engine 16. A shaft 17 driven by said engine is operatively connected to a vertically disposed shaft 18 which is disposed preferably centrally of the framework and a vertically arranged shaft 19 which is arranged rearwardly of said framework and is supported in bearings 20 fixed to said framework.

75 75 Housings 21 are secured to framework 14 and extend rearwardly therefrom and have mounted therein horizontally disposed shafts 80 80 22 which are operatively connected to the vertically disposed shaft 19 and carry propellers 24 which are designed to drive the ship forward. There are preferably four of these housings 21 and propellers 24 85 spaced suitable distances apart from each other as shown in Figure 3.

Shaft 18 extends through and has a bearing in casting 25 and carries at its upper end a propeller 26, which latter is disposed 90 a suitable distance below the lowermost gas bag 10 and is utilized in ascending. Shafts 18 and 19 are controlled in any suitable manner by levers 27 arranged in car 15, whereby either one of said shafts may be connected and disconnected from the engine shaft 17.

95 A rudder 28 extends rearwardly from the airship and is carried by a suitable frame-work 29 which is pivotally connected at 30 to framework 14 so that the rudder 28 and frame 29 when not in use may be folded against said framework 14 by means of a cable 31, one end of which is connected at 32 to frame 29 and the opposite end of which is connected to a pulley 34 arranged in car

105 15 where it may be conveniently operated by the operator.

A pulley 35 is journaled in a suitable bearing 36 which latter is fixed to framework 14 at a suitable point above pivotal connection 30 and cable 31 operates over said pulley. Frame 29 preferably consists

of two spaced members which converge toward the rudder 28, the upper member 29^a being pivotally connected at 30 and the lower member 29^b has its ends resting 5 against the rear uprights of framework 14, as shown in Figure 4. Said ends are preferably provided with pins 36 adapted to enter apertures 37 formed in said uprights. Projecting laterally from each end of members 29^b are pins or rollers 38 which operate 10 in curved slots 39 of arcuate arms 40. These arms are fixed to framework 14 and curve rearwardly and upwardly concentrically with pivotal points 30 and form bearings 15 and guides for the ends of frame members 29^b.

Frame 29 is preferably jointed as at 29^c to allow swinging movement of rudder 28 in horizontal direction which is accomplished by a cable 29^d operatively connected to the rudder section of frame 29 and extending to suitable steering mechanism located in car 15.

The rear supporting connections 12 of members 10 comprise an end plate 41 secured to the rear end of each member 10 and said end plate has an axial extension 42 which is slidably mounted in bearings 43 carried by the rear portion of framework 14. A coiled spring 44 is placed on extension 42 and is interposed between end plate 41 and bearing 40 and permits yielding movement of member 42. Car 15 is preferably provided with wheels 45 by means of 35 which the airship can be moved on the ground.

The provision of a plurality of gas bags and arrangement thereof in vertical plane permits the use of the airship and also permits descending and ascending of the airship in streets or in narrow areas.

The division of the gas containers into a series of independent and comparatively small gas bags provides for greater safety 45 and the damage to one or more gas bags will not incapacitate the airship.

My improved airship is a combined helicopter and an airship and can be operated to move in a substantially vertical plane as in ascending and descending and forward. The construction is such as to enable the airship to require very little space when moving in vertical direction without limiting the carrying capacity thereof.

55 I claim:

1. In a dirigible airship, the combination of a rigid framework, a plurality of gas bags supported by said framework in superimposed relation, a car carried by the lower end of said framework, horizontally disposed propellers mounted in said framework for propelling said airship, a horizontally disposed frame pivotally supported on said framework and extending rearwardly therefrom, and a rudder operatively mounted on

said frame for steering said airship, said frame having operative connection with said framework for permitting the displacement of said frame and rudder in a vertical plane in close proximity to said framework. 70

2. In a dirigible airship, the combination of a framework, a plurality of gas containers arranged in a vertical row in said framework, a car carried by the lower end of said framework, a series of horizontally disposed propellers arranged in said framework for driving said airship, a vertically disposed propeller mounted in said framework for propelling said airship in a vertical plane, a rudder for steering said airship, and a frame pivotally connected to said framework and carrying said rudder, said frame being operable to occupy displaced position in close proximity to said framework so as to reduce the space occupied by said airship 85 while on the ground.

3. In a dirigible airship, the combination of a framework, a plurality of gas containers arranged in a vertical row in said framework, a car carried by the lower end of said framework, a series of horizontally disposed propellers arranged in said framework for driving said airship, a vertically disposed propeller mounted in said framework for propelling said airship in a vertical plane, a rudder for said airship, a frame pivotally connected to said framework and carrying said rudder, said frame being operable to occupy displaced position in close proximity to said framework so as to reduce the space occupied by said airship 100 while on the ground, and means for positioning said rudder in said frame.

4. In a dirigible airship, the combination of a rigid framework, a plurality of gas bags supported by said framework in superimposed relation, a car carried by the lower end of said framework, a series of horizontally disposed propellers spaced in a vertical plane relative to each other and mounted 110 in said framework for propelling said airship, a horizontally disposed frame pivotally supported on said framework and extending rearwardly therefrom, a rudder carried by said frame for steering said airship, and means operable from said car for moving said frame on its pivot from a horizontal extended position into a vertical position against said framework so as to reduce the space occupied by said airship when on 120 ground.

5. In a dirigible airship, the combination of a rigid framework, a plurality of gas bags supported by said framework in superimposed relation, a car carried by the lower end of said framework, a series of horizontally disposed propellers spaced in a vertical plane relative to each other and mounted in said framework for propelling said airship, a horizontally disposed frame pivotally sup- 125 130

ported on said framework and extending rearwardly therefrom, a rudder carried by said frame for steering said airship, means operable from said car for moving said frame on its pivot from horizontal extended position into a vertical position against said framework so as to reduce the space occupied by said airship when on ground, and arcuate

members fixed to said framework concentrically with the pivotal mounting of said frame and engageable by the latter at points spaced from the mounting for guiding and supporting said frame. ¹⁰

In testimony whereof I hereunto affix my signature this 2nd day of October, 1925.

WARREN LEMON.
